LOUIS BREGUET, OF PARIS, FRANCE, ASSIGNOR TO SOCIÉTÉ ANONYME DES ATELIERS D'AVIATION LOUIS BREGUET, OF PARIS, FRANCE.

METHOD AND APPARATUS FOR FACILITATING THE STARTING AND THE LANDING OF AEROPLANES.

Application filed August 23, 1922. Serial No. 583,811.

To all whom it may concern:

Be it known that I, LOUIS BREGUET, a citizen of France, and a resident of Paris, France, have invented new and useful Improvements in Methods and Apparatus for Facilitating the Starting and the Landing of Aeroplanes, which is fully set forth in the following specification.

At the time of starting or landing of an aeroplane, it is necessary that it should bear with the least possible weight upon its landing chassis in order to avoid ruptures when the aeroplane rolls on the ground over obstacles. Absence of wheels would also be a great advantage for an avion, as it could be adapted with facility for combined land and water use, the same fuselage provided with skids or runners being enabled to descend upon land and sea.

In order to obtain this result, the present invention comprises the use of an atmosphere maintained under pressure under each aeroplane wing by means of a suitable air fan or compressor which is driven by the main engine or engines, or even by auxiliary engines. This will dispose between the lower planes in the case of a biplane, or under the single plane in the case of a monoplane, an atmosphere under pressure which is substantially independent of the speed of the avion and may even prevail when the latter is in the stationary position, i. e. when not travelling. In this manner the weight of the avion, even before reaching any speed, will be at once reduced to a very small amount, and the sliding of the skids or keel of the fuselage on the ground may become sufficiently easy to be able to dispense with the use of wheels with their shock-absorbing devices.

The following description, together with the accompanying drawings which are given by way of example, sets forth the present invention.

Fig. 1 is an elevational view of an avion for land and water use which is provided with a device according to the invention, and Fig. 2 is a corresponding front view. Fig. 3 is a modified form of a detail of Fig. 1.

The plane of the avion A, Fig. 1, has coextensive with the active edge a hinge *a* serving as a joint for the movable plane or flap *a b c* which is provided at the end with

a band of leather or india-rubber *b c* intended to sweep over the ground or the surface of the water so as to form a sufficiently tight joint. At the rear part of the plane A is mounted in like manner a flap *d e f*, hinged at *d*, which can be lowered into contact with the ground or the water and may be constituted by a flat member analogous to the front flap or by the end of the main plane itself which is suitably hinged at *d*, Fig. 3; it is also provided at the lower edge with a band of leather or india-rubber. The flap *a b c* is preferably made of flexible material so that when folded up it is enabled to fit upon the curved forward end of the plane.

The respective axles *a, d*, of the flaps *a b c, d e f*, are each provided with various arms *a k, d l* which are connected together in pairs by a rod *k l* whereby the two flaps are enabled to move in co-operation, and said rod serves for the control of the starting and stopping of a machine M such as an air fan, compressor or the like which is driven by the main engine or by a special engine and delivers compressed air between the planes and the ground through a suitable conduit. A spring R is secured to the plane A and to the flap *a b c* and tends to hold the latter constantly open, but it is so disposed as to yield to the pressure on the outer face of said flap which is due to the forward travel of the aeroplane. The said spring has a variable tension which is controlled by the pilot.

Each of the lateral edges of the main plane is provided with a hinge *g*, Fig. 2, serving as a joint for the flap *g h q* which is bordered at the lower edge by a leather or india-rubber band *h q* and is controlled directly by the pilot by a cable *r¹* attached at *h* and disposed on a supporting pulley *r* situated within the main plane A.

When starting the avion, the front, rear and side flaps have the respective positions *a b c, d e f* (Fig. 1) and *g h q* (Fig. 2). The machine M (Fig. 1), delivers air under pressure into the receptacle formed by the plane A, the ground, the flaps *a b c, d e f, g h q*, and this provides a sustaining power which is proportional to the pressure supplied by the compressor and is under the pilot's control. Should the avion be upon the water, it will be lifted out as quickly

as may be desired. The avion will gradually assume its speed of flight, and when this becomes sufficient, the flap *a b c* will close up. The arm *a k* is thus given a circular motion in the counter-clockwise sense and acts upon the rod *k l* so as to draw the arm *d l* in the same sense whereby the flap *d e f* also closes up. When the aeroplane reaches normal speed, the flap *a b c* is applied at *a b¹ c¹* against the lower face of the plane *A*, and the flap *d e f* occupies a like position *d e¹ f¹*. By suitable means the movement of the rod *k l* is caused to stop the compressed air machine *M*. The pilot 10 operates the cables *r¹* to raise the side flaps *g h q* to the position *g h¹ q¹*, Fig. 2. Upon landing, the speed diminishes, and the resistance of the air is thus diminished according to the square of the speed. The 20 spring *R*, Fig. 1, pushes out the flap *a b c* and the latter will automatically operate the starting of the machine *M* by means of the rod *k l*, and hence the flaps *a b c* and *d e f* will be lowered towards the ground. The 25 pilot releases the cable *r¹*, Fig. 2, so as to allow the side flaps *g h q* to assume the vertical position. When all the flaps come close to the ground or the water, the atmosphere under pressure will prevail, and the 30 air delivered by the compressor can only escape through very small outlets, so that the avion will light in an easy manner upon a layer of compressed air which forms in fact an air cushion for this purpose. Furthermore, 35 when the said flaps become extended, this will afford a considerable resistance to forward travel and the aeroplane is thus strongly braked upon the air.

The said arrangement for opening and closing the flaps is given solely by way of example, and it is obvious that the invention may be carried into effect by like devices serving to maintain an atmosphere under pressure between the planes of the 45 avion and the ground.

What I claim is:

1. A device for the starting and landing of aeroplanes when in the immediate vicinity to a landing surface, comprising a receptacle 50 below the wings of the aeroplane formed of a plurality of unfolding surfaces extending in close proximity to the landing surface, said receptacle being open on the side ad-

jacent said landing surface, and means for producing an atmosphere under pressure 55 within said receptacle.

2. A device for the starting and landing of aeroplanes comprising a plurality of hinged walls secured to the lower surface of the wings of said aeroplane, means for moving said walls to such position that the lower edges of the same are in close proximity to the landing surface, and means for compressing air in the receptacle formed by said walls, said receptacle being open on the 60 side adjacent the landing surface.

3. A device for the starting and landing of aeroplanes when in immediate vicinity to the landing surface, comprising two flaps hinged to the lateral edges of the plane, 70 means for controlling said flaps, two flaps hinged to the front and rear edges of the plane, a rod connecting these two flaps, an air compressor under the control of said rod and adapted to deliver compressed air 75 between the said flaps, and a spring adapted to pivot the front longitudinal flap when the speed of the avion becomes reduced.

4. A device for the starting and landing of aeroplanes when in immediate vicinity to the landing surface, comprising two flaps hinged to the lateral edges of the plane, 80 means for controlling said flaps, two flaps hinged to the front and rear edges of the plane, a rod connecting these two flaps, an air compressor under the control of said rod 85 and adapted to pivot the rear longitudinal flap when the speed of the avion becomes reduced, and bands of flexible material disposed along the lower edge of said flaps and 90 insuring the tight working between the pneumatic receptacle formed by the said flaps and the surface upon which the avion effects the landing.

5. The method of lightening the weight 95 on the landing chassis of an aeroplane at the time of starting or landing which consists in forming a receptacle between the landing surface and the lower side of the wings of the aeroplane, utilizing the landing surface for the lower wall of said receptacle, and producing an atmosphere under pressure in said receptacle.

In testimony whereof I have signed this specification.

LOUIS BREGUET.
